(57) **CLAIM**

We claim the ornamental design for a rotary cutter, as shown and described.

DESCRIPTION

FIG. 1 is a front perspective view of a first embodiment of a rotary cutter of the present invention;

FIG. 2 is a front view thereof;

FIG. 3 is a rear view thereof;

FIG. 4 is a top view thereof;

FIG. 5 is a bottom view thereof;

FIG. 6 is a first side view thereof; and,

FIG. 7 is a second side view thereof.

The broken lines in the Figures form no part of the claimed design. The broken line showing the blade is included for purposes of environment and forms no part of the claimed design.
